(57) **CLAIM**

The ornamental design for a bar chair, as shown and described.

DESCRIPTION

FIG. 1 is a perspective view of a bar chair, showing my new design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a partial enlarged view of FIG. 2.

The broken lines in the figures are for the purposes of illustrating portions of the bar chair, which form no part of the claimed design.
